UNITED STATES PATENT OFFICE

150,493

DESIGN FOR A TOY HOUSE

Stanley Chin, New York, N. Y.

Application May 31, 1946, Serial No. 130,251

Term of patent 7 years

(Cl. D34—15)

To all whom it may concern:

Be it known that I, Stanley Chin, a citizen of the United States, residing at 311 West 23rd Street, Manhattan, New York, in the county of New York and State of New York, have invented a new, original, and ornamental Design for Toy House, of which the following is a specification, reference being had to the accompanying drawings, forming part thereof.

Figs. 1 and 2 are perspective views of the house from adjacent corners showing my new design.

The opposite half of the roof is like that shown, while the wall not shown is plain and unornamented.

I claim:

The ornamental design for a toy house, as shown and described.

STANLEY CHIN.
